UNITED STATES PATENT OFFICE.

RICHARD WYLIE, OF NAPA, CALIFORNIA.

SIDEWALK-CURB AND SURFACE-CASE FOR ELECTRIC WIRES.

SPECIFICATION forming part of Letters Patent No. 295,710, dated March 25, 1884.

Application filed December 14, 1883. (No model.)

To all whom it may concern:

Be it known that I, RICHARD WYLIE, of Napa, in the county of Napa and State of California, have invented a new and Improved 5 Sidewalk-Curb and Surface-Case for Electric Wires, of which the following is a full, clear, and exact description.

The object of my invention is to provide a new and improved case for electric wires in 10 the curbs of sidewalks and in the surface of the street at the crossings, whereby the said wires will be out of the way, and will be so located that they can easily be reached in case they are to be repaired or adjusted, or in case 15 additional wires are to be laid or connections are to be made.

The invention consists in a case for electric wires, formed of grooved castings or blocks arranged along the curb and across the streets 20 at the crossings, which blocks or castings are provided with covers which can easily be removed for placing the wires in the blocks or making connections with the wires for repairing breaks, &c.

25 The invention further consists in the combination, with the above-mentioned castings, of corner-pieces for finishing the corners of the streets and establishing communication between the blocks held on the curb and the 30 blocks of the crossing.

The invention also consists in various parts and details and combinations of the same, as will be fully described and set forth herein-after.

35 Reference is to be had to the accompanying drawings, forming part of this specification, in which similar letters of reference indicate corresponding parts in all the figures.

Figure 1 is a perspective view of my improved sidewalk-curb and surface-case for 40 electric wires, showing the manner in which the plates are raised. Fig. 2 is a plan view of the same, showing one of the cover-plates raised. Fig. 3 is a longitudinal elevation of 45 the same on the line xx , Fig. 2, showing the entire case closed. Fig. 4 is a cross-sectional elevation on the line yy , Fig. 2. Fig. 5 is a cross-sectional elevation on the line zz , Fig. 2. Fig. 6 is a perspective view of the corner-piece of the curb.

Along the curb of the sidewalk A blocks or

castings B are arranged, which rest on a base-block, C, the blocks or castings B being provided with a longitudinal central groove, B' , in the upper surface, which groove is preferably made semicircular. From the edges of the groove B' the upper surface of the casting or plate is inclined downward toward each longitudinal edge into pockets B^2 , formed parallel with and one at each side of the groove 60 B' . At its inner longitudinal edge the casting B is provided with an upwardly-projecting flange, D, the upper edge of which is flush with the sidewalk. The bottom of the outer pocket, B^2 , is slightly rounded, as shown, so 65 as to receive a roller, d, formed on the bottom of the outer edge of a cover, E, provided in its under side with a central longitudinal groove, E', and having its bottom inclined downward from the edges of the grooves, so 70 as to fit against the inclined upper surface of the castings B, which cover is of such height that when it rests on the casting B its upper surface will be flush with the sidewalk. At its outer edge the cover E is provided with a 75 shoulder, d' , above the roller d, and the casting B is provided at its outer edge with a flat part, d'' , upon which the shoulder d' of the cover can rest when the cover is raised into a vertical position, as shown in dotted lines 80 in Fig. 4. If the said cover is swung into a vertical position, it will be held in this position until it is swung down again. The flange D is provided in its upper surface and along the inner edge with a rabbet, b, adapted to receive a flange, e, projecting from the inner edge of the cover E at the top of the same.

In the upper edge of the flange D of the casting B a series of notches, b' , are formed for receiving hooks to swing upward the covers E. 90 Each section of the cover E is provided at one end with a rabbet, g, and at the opposite end with a flange, k, fitting against the rabbet of the preceding cover-section. The rabbets g are provided with grooves h, for conducting off 95 the water that leaks through the joints. The upper surface of the cover E is serrated or roughened in any other suitable manner. At the crossing of the street the wires must be carried below the surface of the roadway—100 that is, below the level of the groove in the castings B—and the castings B must have a

corner finish at the corners of the streets. At the corner a casting or block, G, is provided, the upper surface of which is flush with the top of the sidewalk, and the edge of which is 5 rounded according to the shape of the corner, the said block projecting outward from the block B in the shape of a bracket. Below the said block G trough-shaped blocks or castings H are arranged, the upper edges of which 10 are flush with the surface of the roadway-pavement I, the said castings H having a longitudinal groove, H', in the bottom, and having the bottom inclined downward from the upper edge of the groove to form two plates, 15 H² H².

In the casting H a cover, J, fits, which has its bottom inclined to fit against the upper surface of the bottom of the casting H, and is provided with a longitudinal groove, J', which 20 cover J is provided with flanges j at the longitudinal edges, which flanges fit in rabbets in the upper surfaces of the side pieces of the castings H, the upper surface of the cover J being flush with the roadway-pavement. The 25 covers J are also provided with a rabbet at one end and a flange at the other, so as to form close joints. That casting H which passes under the corner-block G is provided at its inner end with an upwardly-inclined end, K, 30 up which the wires can pass into the grooves B' of the castings B. A block, L, having its outer edge rounded the same as the corner, fits in between the surface of the block G and the upper surface of the cover J of that block 35 or casting H below the block G. The block or corner-piece L is provided with a ridge, M, the outer end of which is rounded, and the inner end of which is provided with a rabbet, m, in which a flange, k, of the cover E of the 40 adjoining casting or block B fits, the block G being provided with a rabbet, m', forming a continuation of the rabbet m. The upper surface of the ridge M is flush with the top of the block G, which in turn is flush with the side- 45 walk.

In the inner end of the block L a curved recess, O, is formed, which has its edge beveled downward about parallel with the inclined end K, formed at the end of the first casting H 50 of the crossing, the first cover J being correspondingly cut away at J².

At each side of the recess O shanks O' are formed on the block L, each of which is provided in its bottom surface with a longitudinal groove, o, adapted to receive longitudinal ridges p on the upper surface of the cover J of the first section or casting H of the crossing. The inner prong or shank, O', is provided at its inner edge with a stud, r, which 55 is adapted to pass into a notch, s, formed in the bottom edge of the inner longitudinal ridge or shank of the cover E of that casting or block B adjoining or resting against the corner-block G. The upper surface of the 60 covers J of the castings or blocks H are also serrated or roughened in some suitable manner.

To lay the cables or wires, all the covers E and J are swung up or removed, and the block L is passed out from under the block G, the 70 wires are placed in the grooves B' H', and the corner-block L is passed under the block G, and then the covers E and J are swung down. If the cover E of that casting B adjoining the corner-block is swung down, the projection r 75 of the corner-block L will pass into the notch s of the cover E, whereby the corner-block L will be locked, and displacement in the direction of the length of the cover E will be prevented. The end flange, k, of the cover E 80 passes into the rabbets m m', formed in the corner-blocks L and G. The ends of the covers E overlap each other in the manner described. Then the covers J of the U-shaped pieces H are placed in the said pieces H, and the first 85 cover J is slipped under the corner-block L, the ridges p of the said cover passing into the groove o, and thus preventing lateral displacement of the corner-block L. The remaining covers J are then placed in the castings or 90 blocks H. The end flange of one cover J passes into the rabbet of the adjoining cover. At the middle of the street the covers abut against each other without any end flanges, and from the middle toward the sides of the 95 street the end flanges are always arranged on the ends of the cover-sections toward the curb, the rabbets being formed on the ends toward the middle of the street. The upper edges of the side pieces of the castings or blocks H are 100 provided with notches for admitting hooks for raising the covers J. The covers E can be raised by means of the lever P, to which hook-arms Q are pivoted, as shown in Fig. 1, the hooks of the arms Q passing into the notches 105 b' in the upper edges of the flanges of the castings or blocks B. The covers J can be raised by means of tongs suspended from derricks, as is also shown in Fig. 1. The blocks B and H are provided with suitable apertures to 110 permit the water that collects in the same to flow off. The castings B and H and their covers E and J can be made in sections of various lengths, according to the streets in which they are to be located. The wires held 115 in the case thus formed on the curb and in the surface of the street are entirely out of the way, can be reached very easily for making repairs or connections, and the case gives the curb of the sidewalk a perfect finish.

The shaft of the groove for receiving the wires and the size of the said groove can be varied as circumstances may require.

Having thus described my invention, what I claim as new, and desire to secure by Letters 125 Patent, is—

1. In a case for electric wires, the combination, with a grooved block or casting, of a cover provided with a roller-joint for swinging the cover upward, substantially as herein 130 shown and described.

2. In a case for electric wires, the combination, with a grooved block or casting, of a cover fitting on the said block or casting, and

- provided with a roller-joint, d , and with a shoulder, d' , substantially as herein shown and described.
3. In a case for electric wires, the combination, with a block or casting having a longitudinal groove in the upper surface of its bottom, which upper surface is inclined downward from the edges of the groove, of a cover fitting on the casting or block, and provided with a longitudinal groove in its under side, substantially as herein shown and described.
4. In a case for electric wires, the combination, with the block or casting B , having a flange, D , provided in its upper edge with a rabbet, b , of the cover E , provided with a flange, e , fitting in the rabbet b , substantially as herein shown and described.
5. In a case for electric wires, the combination, with grooved castings held along the curb of the sidewalk and grooved castings located in the street at the crossings, of a corner-block located at the corner of the sidewalk, and establishing communication between the blocks or castings of the curb and the blocks or castings of the street-crossings, substantially as herein shown and described.
6. In a case for electric wires, the combination, with the grooved castings or blocks B H and their covers E J , of corner-blocks establishing communication between the castings B and H , substantially as herein shown and described.
7. In a case for electric wires, the combination, with the grooved castings or blocks B H and their covers E J , of the fixed corner-block G and the removable corner-block L , placed between the fixed corner-block G and the cover of the first casting or block H , substantially as herein shown and described.
8. In a case for electric wires, the combination, with the grooved castings or blocks B H and their covers E J , of the fixed corner-block G and the removable corner-block L , placed between the fixed corner-block G and the cover of the first casting or block H , substantially as herein shown and described.
9. In a case for electric wires, the combination, with the grooved castings or blocks B H and their covers E J , of the fixed corner-block G , provided with a rabbet, m' , and the removable corner-block L , placed between the fixed corner-block G and the cover of the first casting or block H , which corner-block L is provided with a ridge, M , substantially as herein shown and described.
10. In a case for electric wires, the combination, with the grooved castings or blocks B H and their covers E J , of the fixed corner-block G and the removable corner-block L , placed between the fixed corner-block G and the cover of the first casting or block H , which corner-block L is provided with a ridge, M , having a rabbet, m , substantially as herein shown and described.
11. In a case for electric wires, the combination, with a grooved block, B , and a grooved block, H , of the cover E , having a recess or notch, s , the fixed corner-block G , and the removable corner-block L , having a projection, r , adapted to pass into the notch s in the adjoining cover E , substantially as herein shown and described.
12. In a case for electric wires, the combination, with a casting or block, B , and the cover E , of a casting or block, H , and its cover J , the fixed corner-block G , and the removable corner-block L , whereby a continuous groove is formed, substantially as herein shown and described.
